CONDENSER-CONTROL MECHANISM.

Application filed September 17, 1925. Serial No. 56,795.

This invention relates to condensers and control mechanism therefor.

Most radio receiving sets, as is well known, include a plurality of similar units, such as condensers, and it is desirable that means be provided for simultaneously making similar adjustments of all of the units. Moreover, for accurate tuning, it is advantageous to provide for independent minute or vernier 10 adjustments of each unit or condenser.

Certain condensers now in use have separate elements or plates controlled independently of the remaining plates, but such an arrangement cuts down the range of capacity of the condenser.

This invention has for its salient object to provide a condenser control for a plurality of condensers so constructed and arranged that the maximum range or ratio between 20 maximum and minimum capacity can be obtained.

Another object of the invention is to provide a condenser control whereby equal simultaneous adjustments of the movable elements of a plurality of condensers can be effected and an independent vernier adjustment of the movable elements of each condenser can be obtained.

Another object of the invention is to provide simple and practical control means for simultaneously adjusting a plurality of variable condensers and for independently adjusting each of the variable condensers.

Further objects of the invention will appear from the following specification taken in connection with the drawings, which form a part of this application, and in which—

Fig. 1 is a front elevational view of a portion of a panel having mounted thereon 40 condensers controlled in accordance with the invention.

Fig. 2 is a top plan view of the structure shown in Fig. 1, two of the condensers being omitted for the sake of clearness.

Fig. 3 is an enlarged detail elevation showing the vernier adjustment for one of the condensers.

Fig. 4 is a sectional elevation taken through the gearing and central control 50 shaft, and

Fig. 5 is a view similar to Fig. 1, but showing a slightly different embodiment of the invention.

The invention briefly described consists 55 of the combination of a plurality of variable condensers, each having fixed elements and

movable elements and means for simultaneously effecting the adjustment of the movable elements of all of the condensers and means for effecting an independent adjustment of the movable elements of each condenser. Further details of the invention will appear from the following description.

In the embodiment of the invention illustrated in Figs. 1 to 4 inclusive, there are 60 shown four variable condensers A, B, C and D mounted on a panel 10.

The condensers may be of any desired construction, but as illustrated, each condenser comprises a frame 11 secured to the 65 panel and having mounted thereon fixed plates 12. Each condenser also has a spindle or shaft 13 mounted in the frame 11 and the movable plates 14 are secured to the spindle or shaft 13 in any desired manner.

A supporting frame 20 is secured to the central portion of the panel 10 and has bearings 21 and 22 in which is mounted a shaft 23. The shaft 23 has secured thereto 70 a pair of gears 24 and 25.

There are also pivoted on the shaft a plurality of arms 30, 31, 32 and 33, which are shown as L-shaped, the arms 30 and 31 being disposed above the shaft and the arms 75 32 and 33 being disposed below the shaft.

Each arm has rotatably mounted thereon intermediate its ends a gear or pinion, these pinions being indicated as 35, 36, 37 and 38. The pinions 35 and 38 mesh with the gear 24 on opposite sides of the axis thereof 80 and the pinions 36 and 37 mesh with the gear 35 on opposite sides of the axis of said gear.

Pinions 35, 36, 37 and 38 have meshing 85 therewith racks 40, 41, 42 and 43, the racks being mounted between the arms and in-turned ends 45 formed on or carried by the arms.

In order to maintain the racks in mesh with the pinions, each arm has secured to 90 its outer end a spring strip 46 which engages the outer surface of the rack.

Each of the condenser shafts 13 has secured thereto a pinion 50 adapted to mesh with one of the racks 40, 41, 42 or 43 and 95 the racks are held in mesh with the pinions 50 by means of spring strips 51 carried by arms 52 which in turn are pivoted on the shafts 13.

Since the gears 37 and 38 are on the opposite side of the axis of the actuating gears 110 24 and 25 from the gears 35 and 36 and it

will be noted that the racks 42 and 43 engage the pinions or gears 50 on the shafts 13 of the condensers B and C below the shaft whereas the racks 40 and 41 engage the gears 50 of the condensers A and D above the shafts 13.

5 The master control shaft 23 extends through the panel as shown in Fig. 4 and has secured to its outer end a knob 55.

- 10 When the shaft 23 is rotated, it will be obvious that the gears 24 and 25 will communicate the rotation of the shaft through pinions 35, 36, 37 and 38 and racks 40, 41, 42 and 43 to the shafts 13 of the condensers 15 A, B, C and D, thereby effecting an equal simultaneous adjustment of the movable plates of all of these condensers.

Vernier adjustment.

- 20 It is also desirable as hereinbefore stated to provide for a minute or vernier adjustment of each condenser. This is accomplished in the embodiment of the invention shown in Figs. 1 to 4 by means of four vernier shafts or spindles 60, 61, 62 and 63 which are disposed around the master control shaft 23. Each of the vernier shafts or spindles has secured thereto a disk 65 and the disks 65 are eccentrically connected to the arms 30, 31, 32 and 33 by means of links 66. It will be noted that each of the links 66 is pivoted to its arm at a point 67 intermediate the free end of the arm and the pivotal connection of the arm to the shaft 23.

- 35 Referring to Fig. 3, it will be noted that the arm shown therein can be oscillated through an angle indicated as α by means of adjusting the vernier spindle 62. It will be evident that the movable plates of any of 40 the four condensers can be given a minute or vernier adjustment by rotating or oscillating the vernier spindle associated with that condenser.

In Fig. 5, a slightly different form of the 45 invention is illustrated in which the various adjustments above described are accomplished by means of levers instead of by means of gears, pinions and racks.

In this form of the invention, the master 50 control shaft 70 has connected thereto an arm 71 which in turn is connected by a link 72 to an arm 73. The arm 73 is pivotally supported by an arm 74 mounted on a fixed pivot 75 and connected to the arm 73 intermediate its ends at 76. The upper end 77 of

the arm 73 is connected by a link 78 to an arm 79 which in turn is secured to the condenser spindle or shaft 80 of condenser C, four condensers A, B, C and D being shown.

5 In order to effect a vernier adjustment of the condenser C, a vernier spindle 81 has a disk 82 secured thereto which in turn is eccentrically connected by a link 83 to the point 76 on the arm. By oscillating the spindle 81, the arm 73 can be swung on the link 74, thus effecting a slight or minute movement of the movable plates of condenser C.

10 Each of the condensers A, B, C and D is adjusted in a similar manner and each arm 73 of the linkage connected to each condenser is connected by linkage 85 to the arm 71 carried by the master control shaft 70.

15 With the embodiment of the invention shown in Fig. 5, it will be obvious that rotation of the master control shaft 70 will effect an equal simultaneous adjustment of the movable plates of each condenser and, furthermore, an independent vernier adjustment of each condenser can be accomplished by 20 rotating or oscillating the vernier spindle 81 connected to that condenser.

25 Although certain specific embodiments of the invention have been particularly shown and described, it will be understood that the invention is capable of modification and that changes in the construction and in the arrangement of the various cooperating parts may be made without departing from the spirit or scope of the invention, as expressed 30 in the following claim.

What I claim is:

35 A plurality of variable condensers, each having a movable element, a master control shaft, separate mechanisms connecting said shaft and each of said movable elements to cause movement of the master control shaft to be imparted to each of the movable elements of the several condensers, a part of 40 each connecting mechanism being arranged to rotate about an adjustable point, the position of which point determines the location of the movable element of its respective condenser relative to the master control shaft, and means for changing the position of each 45 of said adjustable points.

50 In witness whereof, I have hereunto set my hand this first day of August, 1925.

CARL E. TRUBE.
